SPOOL BRACKET FOR WINDING MACHINES

Howard W. Taylor, Westerly, R. I., assignor to
The Atwood Machine Company, Stonington,
Conn., a corporation of New Jersey

Application October 27, 1936, Serial No. 107,777

5 Claims. (Cl. 242—18)

This invention relates to textile winding machines and particularly to machines for winding silk or other yarn upon spools having flanges at opposite ends and the spools having also a central spindle the ends of which extend shortly behind the flanges.

An object of the present invention is to provide an improved spool supporting bracket for winding machines which may be cheaply made and which will provide an oilless bearing surface for the spool spindle ends during the winding operation.

Another object of the invention is to provide a detachable end piece for a spool supporting bracket which when worn or damaged may be removed and another end piece substituted therefore at a minimum expense.

Another object of the invention is to provide bearings for the extended spindle ends of the bobbins that will be non-metallic and thus entirely rust proof so that no rust will be formed that might be transferred to and damage the yarn being wound upon the bobbins.

And finally it is an object of the invention to provide a rigid moulded fibre member for the end piece of a spool supporting bracket having flanges thereon extending laterally and forming with the end face of the bracket substantially vertically disposed recesses or slots within which the spindle ends of the spools may ride upward as the spools fill with the yarn and be retained during the winding operation against lateral movement.

A feature of importance of the invention and which enables the above objects to be accomplished is that the spool supporting ends of the brackets of a winding or twisting machine are surfaced so that in their operative positions the end faces of the brackets will be in a substantially vertical plane parallel to the longitudinal members of the winding machine. This surface preferably has a central groove or shallow recess which serves as a supporting surface for a detachable member having the central web of the member entering the groove or recess. This detachable member is preferably of moulded fibre requiring no lubrication or may be of any well-known oil-less metal bearing. This member has oppositely disposed laterally extending flanges which are spaced from the end face of the bracket and which form with the end face the necessary guideway or space for the spindle ends of the spools being wound. As the winding pressure is always against the inner surface of the flange during the winding operation and away from

the end faces of the brackets the detachable member takes all of the wear of the spindle. When worn this member costing but little may be quickly replaced and the guideway may thus be restored to its original condition, position and dimension.

With the above and other objects in view the invention may include the features of construction and operation set forth in the following specification and illustrated in the accompanying drawing.

In the accompanying drawing annexed hereto and forming a part of this specification, the invention is shown embodied in a spool winding machine for textile yarn of standard form but it will be understood that the invention can be otherwise embodied and that the drawing is not to be construed as defining or limiting the scope of the invention, the claims appended to this specification being relied upon for that purpose.

In the drawing Fig. 1 is a plan view of a portion of a spool winding machine having the improved spool supporting bracket and guide shown in position thereon; and

Fig. 2 is a side elevation of the parts shown in Fig. 1 partly in section.

Briefly, and in its preferred aspect, the invention may include the following principal parts; first a spool supporting bracket of the general form now used in standard winding machines, the spool supporting end or ends only being modified; and second, a detachable member secured to the end face of the bracket, this member preferably being moulded and of such material as will not require lubrication to be supplied thereto and forming with the end face of the bracket a substantially vertical slot or recess on each side of the bracket within which the spindle ends of spools being wound may extend and be retained while movable upward as the spool becomes filled with yarn. The recess formed by each flange is sufficiently deep to accommodate the spindle end of a spool and with the opposite recess of an adjacent bracket will prevent endwise movement of a spool.

Referring more in detail to the figures of the drawing there is provided a spool supporting bracket 10 attached as shown in the usual manner to the frame members 11 of a winding machine. It will be understood that there are a plurality of these brackets 10 disposed parallel to each other and uniformly spaced longitudinally of the machine. The winding machine may be of any standard form for winding, twisting, doubling or spinning textile yarns and each bracket 10 may

be similar to the others. For that reason but one pair of brackets 10 for supporting a spool 12 is shown.

Below the brackets 10 are traverse rod supporting brackets 13 having rollers 14 on which a traverse bar or rod 15 may reciprocate. Supported below the brackets 10 and 13 is a driving shaft 16 having friction wheels 17 adapted to engage and rotate the individual spools 12. In the form of machine shown in the drawing the friction wheels 17 directly contact the yarn being wound which is supplied to the spools 12 from any position (not shown) and passes over a guide 18 on the traverse bar 15 prior to being wound 15 on the spools.

Each of the spools 12 is provided with central spindles having ends 19 extending from each end flange of the spool. It is by means of these extensions 19 that the spools 12 are held properly positioned during the winding operation.

The end face 20 of each bracket 10 is finished by being milled or planed so that in position this surface is vertical and substantially parallel to the longitudinal axis of the machine. Also formed 25 on this end face is a shallow and narrow slot or recess 21 extending the full vertical length of the surface and disposed centrally thereof. Secured to this end face is a T shaped member 22 preferably having a central web portion entering the 30 groove or recess 21. Laterally extending flanges 23 of the member 22 extend parallel to the end faces 20 on opposite sides of the groove or recess 21. There are thus formed on opposite sides of the brackets 10 substantially vertical guideways 35 24 within which the spindle extensions 19 may enter and guide and support the spools 12. With the spool 12 disposed as shown in Fig. 2 and with the driving wheel 17 rotating upon the axis and in the direction as shown the pressure of the extension 19 during the winding operation will be 40 against the member 22. All wear due to this pressure will occur on the member 22 rather than upon the end faces 20 of the brackets 10. By replacing the members 22 when worn the spools 12 will be 45 properly guided at all times without replacement of the complete brackets 10.

The members 22 may preferably be formed of integrally moulded material not requiring subsequent machine operations. Textile fibres or fabrics moulded in a phenolic condensate such as Bakelite or other well-known composition may be used. Preferably a composition is chosen which

will not require lubrication to be periodically supplied. Metallic, or metallic and graphitic compositions are also suitable. In any case the members 22 are durable and rigid enough to be secured to the brackets by several screws 25 extending through their central webs and being threaded into the forward end faces 20 of the brackets 10. 5

I claim:

1. A spool bracket for winding machines having at its spool engaging end a moulded fibre bearing member detachably secured thereto and forming with the end face of said bracket oppositely disposed vertically inclined recesses within which the extended ends of adjacent spool spindles may be disposed during the winding operation. 10

2. A spool bracket for winding machines having at its spool engaging end a moulded fibre bearing member detachably secured thereto and forming with the end face of said bracket a vertically inclined recess within which the extended end of a 20 spool spindle may be disposed during the winding operation.

3. A spool bracket for winding machines having at its spool engaging end a flat surface, a fibre bearing member attached to said end of the 25 bracket having a laterally extending flange thereon, the flange forming with said end face a substantially vertical recess within which the extended end of a spool spindle may be disposed during the winding operation. 30

4. A spool bracket for winding machines having at its spool engaging end a detachably secured bearing member, said member having laterally extending flanges thereon spaced a short distance from the end face of said bracket whereby the 35 extended spindle end of a spool may be disposed within the recess between said bracket end face and a flange, a central web portion on said member, and securing means for said member passing through said web portion. 40

5. A spool bracket for winding machines having at its spool engaging end a detachably secured fibre bearing member, said member having a central portion engaging and secured to the bracket within a slot provided in the end face thereof, and 45 flanges formed on said bearing member forming substantially vertical uniformly wide recesses on opposite sides of the bracket, whereby the extended ends of spool spindles may engage therein during the winding operation. 50

HOWARD W. TAYLOR.
